United States Patent Office.

CASSIUS M. DRURY, OF GRANBY, NEW YORK.

Design No. 4,687, dated February 28, 1871.

DESIGN FOR A WINDOW-SASH HOLDER.

The Schedule referred to in these Letters Patent and making part of the same.

To all whom it may concern:

Be it known that I, CASSIUS M. DRURY, of the town of Granby, county of Oswego and State of New York, have invented a new Design for a Combined Window-Sash Lock and Holder; and I do hereby declare that the following is a full, clear, and exact description of the same, reference being had to the accompanying drawing forming part of this specification.

My invention consists of a new design for a sash-fastener, said fastener consisting of a piece of metal of an oblong form, having a lip, *a*, projecting from one edge at one end, and having a slot extending

lengthwise nearly its whole length, as shown in Figure 1.

The fastening thus made is applied to the window-frame, close alongside of the sash, as represented in Figures 2 and 3, the former showing it holding the sash down, and fig. 3 showing it holding the sash up.

What I claim is—

The herein-described design for a sash-fastener.

CASSIUS M. DRURY.
